FURNACE HAVING SECTIONALLY SUPPORTED SIDE WALLS

Alfred G. Bildstein, Brooklyn, N. Y., assignor to American Arch Company, New York, N. Y., a corporation of Delaware

Application July 21, 1931. Serial No. 552,189

4 Claims. (Cl. 122—6)

This invention relates to furnaces having sectionally supported side walls.

In general, the present invention has in view improving combustion as well as steaming or heat absorbing conditions.

More specifically, it is an object of this invention to provide a sturdy and yet easily erected or installed sectionally supported furnace side wall in which wall protecting or heat absorbing water tubes are disposed in the vicinity of the fuel burning means of the furnace.

Further objects of this invention will be more apparent if it be borne in mind that in many furnace installations (for example, in an installation of the stoker or grate type) the fuel burning means extends adjacent at least two substantially independently supported sections of the furnace wall and, in many instances, adjacent to as many as six wall sections.

20 In constructions of this general type which have been contemplated heretofore, (i. e., where tubes were disposed closely adjacent a wall in the vicinity of the fuel burning means) the support for the wall bricks has been very seriously complicated, the complication resulting, at least in large part, from the necessity of using different types of mounting structures for the wall bricks in areas remote from and adjacent to the area or region in which the cooling tubes are disposed.

30 With the foregoing in mind, the present invention makes provision for the use of uniform supporting means for a plurality of superimposed side wall sections, each substantially independently supported, the wall structure as a whole being arranged in such manner as to neatly cooperate with cooling tubes which may be extended adjacent to a plurality of wall sections at substantially any desired angle. According to this invention, wall structures of the type referred to 40 (including cooling elements extended adjacent thereto) may be built up and supported in sections in such manner that the application of the cooling tubes does not interfere with proper expansion and contraction of the individual blocks as well as of the sections as units under the influence of changes in temperature.

The foregoing more or less general objects and advantages, as well as others which will occur to those skilled in the art, will become more apparent from a consideration of the following description making reference to the accompanying drawing, in which

Figure 1 is a somewhat diagrammatic vertical sectional view through a furnace construction embodying various features of the invention, certain portions or parts being broken away in order to disclose others lying therebehind; and

Figure 2 is a vertical sectional view taken substantially as indicated by the section line 2—2 on Figure 1.

Making reference first to Figure 1, it will be seen that the furnace here shown includes a stoker structure fragmentarily indicated at 3, the same being extended adjacent to one of the side walls at a substantial angle with respect to the horizontal, so that the grate surface comes adjacent to or passes across a plurality of substantially independently supported sections of the wall. Figure 1 also includes a fragmentary showing at 3a of fuel hopper and feed mechanism. Since this structure may take any desired and well known form, it is not shown in detail herein.

While I have illustrated the application, in accordance with the present invention, of a plurality of water circulating elements to the furnace side wall adjacent a specific type of stoker structure, it should be understood at this point that where the fuel burning means takes some other form, it may be desirable to alter the disposition 75 or extension of the cooling tubes. The invention is also adaptable to such other furnace installations, as will be more apparent as this description proceeds.

In Figures 1 and 2 I have shown a bank or row 85 of water cooling tubes 4 which are extended in a somewhat elongated area paralleling the stoker structure 3. In the preferred arrangement, the overall or total tube area is disposed in such manner that the major portion thereof is extended above the upper surface of the stoker.

Before proceeding with a discussion of the manner in which these tubes are disposed in combination with the independent wall sections, attention is called to the construction of the sections themselves.

As seen most clearly in Figure 2, the furnace side walls may be supported as by means of vertical columns 5 which carry a plurality of horizontally extending and vertically spaced supporting members 6, in this instance of channel form. The members 6, in turn, serve to support the hanger devices 7, such hanger devices being multiplied horizontally along each one of the channels 6 to form superimposed series thereof. The hanger devices of one series, furthermore, are supported or positioned laterally by engagement with abutments 9 of subjacent hangers.

If desired, an outer wall or sheathing 10 may be provided and supported, at least in part, by means of the horizontal supports 6.

The inner or sectionally supported wall structure is composed of a plurality of bricks or blocks 11, each having outwardly projecting portions which are adapted to be received in sockets 12 former at the lower ends of the individual hangers. As here shown, the sockets 12 are formed to be disposed entirely outside of the general plane of the outer surface of the wall, but it should be observed that this structure forms no 115 120

part of the present invention per se, since it is described and claimed in the copending application of Philip W. Antil, Serial No. 547,047, filed June 26, 1931, assignor to the assignee of this application. Each section further includes a plurality of bricks such as those indicated at 13 or 13a which rest on the supporting blocks 11. Expansion joints 14 may be provided between the adjacent bricks or adjacent wall sections.

Attention is now called to the fact that the wall bricks 13a which are disposed in the vicinity of the water tubes 4 are of somewhat smaller depth or thickness than the bricks in the wall sections remote from the tubes 4. In this way a recess is provided in the wall sections in which the cooling tubes are at least partially received, so that the inner surface of the wall, considered as a whole, does not have any tubes or the like projecting inwardly therefrom. It might here be noted that this arrangement is of advantage since it reduces complication in the installation of fuel burning means such as the stoker indicated by the reference numeral 3 in Figure 1.

It should also be observed, at this point, that the various wall bricks 13 and 13a need differ from each other only in the matter of thickness or depth, the structure thereof preferably being entirely similar as between the two types, with this one exception. In this way, the support of the various bricks throughout the entire wall structure is greatly simplified, since only one type of supporting block as well as hanger or suspension devices need be employed throughout. The foregoing arrangement, therefore, affords maximum convenience and simplicity in the matters of construction, erection and the carrying of repair parts as will be apparent to those skilled in the art.

In addition to the foregoing I preferably dispose a lining or veneer of relatively highly refractory blocks or bricks between the sectionally supported wall bricks themselves and the cooling tubes. Such veneer bricks may include any suitable highly refractory material such, for example, as carborundum, silicon carbide, high alumina, or compounds thereof.

In the preferred arrangement, and as shown in the drawing, the veneer bricks take the form of square or oblong block 15 each having grooves formed at opposite and parallel edges thereof. When these bricks are built up as indicated, for example in Figure 2, the grooves cooperate with each other to form longitudinally extended and rounded cavities in which the tubes 4 are seated. This structure, therefore, provides for the positioning of the blocks 15 by engagement with the tubes 4, so that the disposition of the veneer between the tubes and the blocks of the wall sections does not interfere with proper expansion and contraction of the wall bricks under the influence of temperature changes. In other words, the veneer bricks 15 have freedom for expansion and contraction in various different directions independently of expansion and contraction of the wall sections as units or of the individual blocks of which such sections are built up. At the same time, these bricks 15 tend to maintain the proper position and spacing of the tubes.

While, as above indicated, I prefer to form the veneer bricks 15 of relatively highly refractory material as compared with the various wall bricks themselves (11, 13 and 13a), at the same time, in installations where the temperatures contemplated are not excessive, I may use bricks in the form of those indicated by the reference numeral

15 composed of refractory material having substantially the same heat resisting characteristics as the remainder of the wall structure. The wall section blocks may, of course, be formed of any of the suitable and well known fire clays, in accordance with commonly accepted practice.

Where relatively high temperatures are contemplated, and also in any other installations in which slag or clinker formation may be troublesome, I prefer to use relatively highly refractory material as a veneer between the water tubes and the main body of the wall. This use reduces clinker adherence to the wall blocks and yet does not unduly increase the total cost of the installation, since the highly refractory material is applied preferably only in the form of a thin layer in the zone of highest temperature or in the region in which clinker adherence has heretofore been most troublesome.

Thus by the combination of cooling tubes with a highly refractory lining wall in the region of high temperature, I am enabled to materially improve combustion conditions generally, as well as to reduce difficulties heretofore encountered as a result of clinker adherence. These advantages, it is especially noted, are obtained, in accordance with the present invention, in a wall structure which is built up in substantially independently supported sections, in spite of the fact that the high temperature region or zone may be extended across or at least within a plurality of superjacent sections.

In addition to the improvements resulting from reduction of clinker adherence, cooling of the walls and the like, the structure of the present invention provides for improved steaming conditions, as the cooling tubes 4 may readily be connected into the circulation of any suitable boiler with which the furnace proper is associated.

In conclusion, it should be observed that the structure of this invention provides for the disposition of wall cooling and heat absorbing tubes, in a high temperature region, the said tubes and their immediately associated highly refractory bricks being arranged to neatly cooperate with a wall structure of the sectionally supported type without complicating the supporting elements themselves and without interfering with independent expansion and contraction of the main body of the wall sections as well as of the highly refractory bricks themselves. As will also be apparent, the foregoing advantages are obtained without unduly complicating the brick or block shapes, it being noted that the wall structure may be made up of bricks of substantially uniform shape and characteristics throughout the entire wall area with the exception of a mere difference in thickness or depth of the blocks in one area as compared with another.

What I claim is:—

1. A furnace including a sectionally supported side wall, fuel burning means in the furnace adjacent said wall, and water tubes extended along the wall adjacent to the burning means, said wall being composed of refractory bricks some of which, adjacent said burning means, are of smaller depth than bricks in other wall areas to provide a recess in the wall, and the said tubes being received, at least partially, within said recess, the said smaller depth bricks and bricks in other wall areas being of substantially uniform construction, with the exception of difference in thickness, to provide for uniform wall brick support in areas adjacent to as well as remote from said burning means.

2. For a furnace having a grate therein extended at an angle to the horizontal, a wall structure adjacent one side of said grate, said structure including outer supporting means, an inner refractory wall supported by said means in horizontally extending and vertically superimposed sections, each of said sections being composed of a plurality of bricks and having supporting means therefor providing for expansion and contraction of the bricks in each section independently of those in an adjacent section, said sections further being of such vertical dimension as compared with the extension and angularity of the grate that the grate lies adjacent to bricks of a plurality of said sections, the bricks of said plurality of sections in an elongated zone of the wall above and substantially paralleling the grate being of smaller depth than bricks of the sections in other portions of the wall, metallic heat absorbing tubes lying closely adjacent said bricks of smaller depth, said tubes being disposed at least in large part outwardly of the inner surface of the aforesaid other portions of the wall. 80
- 10 15 20 25 30 35 40 45 50 55 60 65 70 75
- plurality of said sections, the bricks of said plurality of sections in an elongated zone of the wall above and substantially paralleling the grate being of smaller depth than bricks of the sections in other portions of the wall, metallic heat absorbing tubes lying closely adjacent said bricks of smaller depth, said tubes being disposed at least in large part outwardly of the inner surface of the aforesaid other portions of the wall, and additional refractory bricks lying between said tubes and the wall bricks of smaller depth, said additional bricks being grooved to fit said tubes, whereby said additional bricks serve to space said tubes and whereby the tubes serve to position the said additional bricks even during expansion and contraction of the bricks of the several wall sections. 85 90 95 100 105 110 115
3. For a furnace having a grate therein extended at an angle to the horizontal, a wall structure adjacent one side of said grate, said structure including outer supporting means, an inner refractory wall supported by said means in horizontally extending and vertically superimposed sections, each of said sections being composed of a plurality of bricks and having supporting means therefor providing for expansion and contraction of the bricks in each section independently of those in an adjacent section, said sections further being of such vertical dimension as compared with the extension and angularity of the grate that the grate lies adjacent to bricks of a 100 105 110 115
